DISCHARGER FOR PYROTECHNIC CARTRIDGES

John L. Lockheed and Miles C. Benner,
Springfield, Mass.

Application November 27, 1940, Serial No. 367,409

7 Claims. (Cl. 89—1)

(Granted under the act of March 3, 1883, as
amended April 30, 1928; 370 O. G. 757)

The invention described herein may be manufactured and used by or for the Government for governmental purposes, without the payment to us of any royalty thereon.

This invention relates to a discharger for pyrotechnic cartridges and the like.

The purpose of the invention is to provide a simple and inexpensive discharger in which a firing pin is cocked and released by retraction of a sleeve on a barrel.

The specific nature of the invention as well as other objects and advantages thereof will clearly appear from a description of a preferred embodiment as shown in the accompanying drawing in which:

Fig. 1 is a view partly in side elevation and partly in section of a discharger with the firing pin in normal fired position;

Fig. 2 is a sectional view on the line 2—2 of Fig. 1;

Fig. 3 is a view partly in elevation and partly in section of the sear;

Fig. 4 is a plan view of the sear spring;

Fig. 5 is a view in side elevation of the firing pin.

Referring to the drawing by characters of reference there is shown a barrel 5 having its breech portion internally threaded for receiving a breech plug 6. The breech plug is formed with an axial chamber 7 for slidably housing a firing pin 8 whose front end enters a tapered aperture in the plug and comes to rest with its point 9 projecting into the cartridge chamber of the barrel. The firing pin is normally held in fired position by means of a helical spring 10 which is partially disposed in a recess 11 in the firing pin and is confined by a plug 12 threaded into the breech plug and closing the chamber.

The firing pin is formed with a front collar 13 and a rear collar 14 for slidably engaging the wall of the chamber 7. A longitudinal slot 15 is formed in the outer wall of the firing pin and extends through the collars while midway between the collars there are provided opposite branch slots 16—16. An arcuate leaf spring 17 is insertable in the slot 15 and includes opposed arms 18—18 at a central portion fitting in the branch slots 16.

A curved sear 19 confined between the collars 13—14 is formed with reduced ends 20—20 which are disposed in the slot 15 in the collars. The leaf spring 17 is confined by the sear and normally tends to move the sear in a radial direction away from the firing pin and into engagement with the wall of the chamber 7 as clearly shown

in Fig. 2. A bent inclined finger 21 punched out of the material of the sear projects outwardly into an aperture 22 in the wall of the breech plug.

5 A sleeve 23 slidably mounted on the barrel and breech plug threadedly carries a pin 24 which projects into the aperture 22 in the breech plug. The inner end of the pin engages the front edge of the finger whereby retraction of the sleeve produces retraction of the firing pin against the action of the spring 10. During the final portion of the rearward movement of the firing pin the bent finger 21 strikes the beveled shoulder 25 at the lower inner edge of the aperture 22 and is cammed inwardly out of engagement with the actuating pin 24. Immediately upon release of the finger the firing pin is driven forwardly under the influence of the energized spring to fire a cartridge in the barrel.

20 Actuating pin 24 is provided with screw threads, as shown, so that the pin may be removed for disassembling the discharger, or may be adjusted inwardly or outwardly to regulate the point of disengagement of finger 21 with the pin when the piece is fired.

25 The inner wall of the chamber 7 is formed with a longitudinally extending groove 26 below the shoulder 25 for receiving the extremity of the finger when it is moved inwardly out of engagement with the actuating pin.

30 After a cartridge has been fired the firing pin remains in the forward fired position. The pin 24 which is now at the lower end of the aperture 22 is moved forwardly to reengage the front edge of the finger, the finger and sear yielding inwardly to permit passage of the pin. The parts are now in the position shown in Fig. 1.

We claim:

1. In a discharger, a barrel, a breech plug in the barrel having an axial chamber and an aperture in its side wall communicating with the chamber, a firing pin slidably mounted in the chamber of the breech plug and having a front and a rear collar, the outer wall of the firing pin formed with a longitudinal slot extending through the collars and with opposite branch slots midway of the longitudinal slot, a firing pin spring, an arcuate leaf spring having opposite arms disposed in the opposite branch slots, a sear disposed between the collars and having reduced extremities disposed in the slot in the collars, a bent finger on the sear projecting into the aperture in the breech plug, a sleeve slidably on the barrel, and an actuating pin carried by the sleeve and engageable with the bent finger.

2. In a discharger, a barrel having a closed breech with a side aperture, a firing pin movable axially in the breech, a firing pin spring, a sear carried in the side of the firing pin and mounted for movement radially thereof, a spring normally urging the sear to an outer position, an inclined finger on the sear projecting into the side aperture of the breech, a sleeve slidable on the barrel, and an adjustable actuating pin carried by the sleeve and engageable with the bent finger to move it against the lower wall of the side aperture in the breech.

3. In a discharger, a barrel having a closed breech with a side aperture, a firing pin movable axially in the breech, a firing pin spring, a 15 radially movable sear carried in the outer side of the firing pin and inwardly movable by engagement with the lower wall of the side aperture, a sleeve on the barrel, and an adjustable actuating member on the sleeve projecting into the side aperture for retracting the sear into engagement with the lower wall of the side aperture.

4. In a discharger, a barrel, a breech plug in the barrel having an axial chamber and an aperture in its side wall communicating with the chamber, a firing pin slidably mounted in the chamber of the breech plug and having a front and rear collar, the outer wall of the firing pin formed with a longitudinal slot extending through the collars, a firing pin spring, resilient means disposed in the slot, a sear contacting said means disposed between the collars and having reduced extremities disposed in the slot in the collars, a bent finger on the sear projecting into the aperture in the breech plug, a sleeve slidable on the barrel, and an actuating pin carried by the sleeve and engageable with the bent finger.

5. In a discharger, a barrel, a breech plug in the barrel having an axial chamber and an aperture in its side wall communicating with the chamber, a firing pin slidably mounted in the chamber and having a recess on the exterior thereof, a spring seated in the recess, a sear 40 confined in the recess in contact with the spring,

said recess adapted to restrain the sear against movement along the axis of the pin and permitting radial movement therein against the resistance of the spring, a firing pin spring, an inclined projection on the sear extending into the aperture in the breech, a sleeve slidable on the barrel, an adjustable actuating member carried by the sleeve and engageable with the inclined projection, said sleeve and member arranged to depress the sear and firing pin against the resistance of the firing pin spring, said inclined projection arranged to engage the lower wall of the side aperture of the breech at the end of the traverse of the sear whereby the sear and firing pin are released and thrust to the firing position.

6. In a discharger, a barrel, a breech plug in the barrel having an axial chamber and an aperture in its side wall communicating with the chamber, a firing pin slidably mounted in the chamber of the breech plug, a firing pin spring, a sear confined in the outer wall of the pin and arranged for conjoint axial movement therewith, resilient means seated in the outer wall of the pin, said sear also having radial movement in the pin against the resistance of the resilient means, a bent finger on the sear projecting into the aperture in the breech plug, means slidable on the barrel, and an adjustable actuating pin carried by said means and engageable with the bent finger.

7. In a discharger, a barrel having a closed breech with a side aperture, a firing pin movable axially in the breech, a firing pin spring, a sleeve on the barrel, a sear element and a complementary sear engaging element, one of said elements carried by said firing pin and the other of said elements carried by said sleeve and engageable through said aperture, and a sear disengaging cam on the wall of said side aperture, said sear engaging element being adjustable with respect to said sear element to regulate their point of disengagement and positioned for adjustment exteriorly of the discharger.

JOHN L. LOCHHEAD,
MILES C. BENNER.
